TOY PARACHUTE

Betty B. Clark, Helena, Mont.

Application October 24, 1952, Serial No. 316,750

1 Claim. (Cl. 244—148)

My invention relates to children's toys or amusement devices, and provides a toy parachute and pack therefor.

The primary object of my invention is the provision of a device of the type above described which has the appearance of a full-sized operative parachute, and which has a harness which may be gotten into and out of by even a child.

A still further object of my invention is the provision of a device of the class described which has a pack which may be readily opened by a child so as to drop out therefrom, under the action of gravity, the toy chute or canopy.

A still further object of my invention is the provision of a device of the class described which is inexpensive to produce, and is light in weight but durable.

The above and still further objects of my invention will become apparent from the following detailed specification, appended claim and attached drawings.

Referring to the drawings wherein like characters indicate like parts throughout the several views:

Fig. 1 is a view in front elevation of my novel structure with the chute in unpacked condition, and some parts being broken away;

Fig. 2 is a view in rear elevation of my device, the same being packed and harnessed to a wearer;

Fig. 3 is an enlarged view in front elevation; and

Fig. 4 is a view in rear plan on the same scale as Fig. 3 but showing the method of opening the pack, some parts being broken away.

Referring with greater particularity to the drawings, the numeral 1 indicates in its entirety a pack including a rectangular back element 2, side flaps 3 and 4 stitched, or otherwise secured, to the back element 2, and upper and lower end flaps 5 and 6 respectively. Elements 2, 3, 4, 5 and 6 may be formed from any flexible sheet material, such as canvas or plastic. As shown, the side flaps 3 and 4 are substantially the same shape and size as the back element 2. On the other hand, the upper and lower end flaps 5 and 6 are substantially the same width as the back element 2, but have a depth substantially less than one-half the depth of the back element 2, for a purpose which will hereinafter become apparent.

A plurality of shroud lines 7 have one end secured by stitching, or the like, to a reinforcing intermediate portion 8 on the back element 2. The other ends of the shroud lines 7 are secured at circumferentially-spaced points to the peripheral edge 9 of a generally circular canopy or chute 10. Cooperating snap-fastener elements 11 and 12 are secured to the side flaps 3 and 4, the former, and preferably the male elements, being located adjacent the side edge 13 of the flap 3 midway between the upper and lower edges 14 and 15. Snap-fastener element 12, preferably the female element, is located adjacent the inner edge 16 of the side flap 4, also preferably midway between the upper and lower edge portions 17 and 18 respectively thereof. A rip cord 19 has one end secured to the outer surface 20 of the side flap 3 closely adjacent the snap-fastener element 11.

As a harness for the above described structure, I provide a belt or girth strap 21, which, at its intermediate portion, is rigidly stitched, or otherwise secured, to the bottom edge portion of back element 2, as indicated at 22. Portion 22 thus becomes the rear portion of the belt 21 while the free ends 23 and 24 become the front ends of the belt 21. Portions 23 and 24 are likewise provided with cooperating snap fastener elements 25 and 26 respectively. A pair of elongated shoulder straps 27 have one of their ends secured by stitching, or the like, to the front portions

2

of the belt 21, one on each side of the snap-fastener elements 25 and 26, as indicated by the numeral 28. The opposite end portions of the shoulder straps 27 are crossed, as at 29, and are stitched to the back element 2, and have their extreme lower ends secured to the rear portion of the belt 21, as indicated at 30.

To pack the chute 10 and shroud lines 7 within the pack 1, they are folded, preferably neatly so as to conform substantially to the shape of the back element 2. When so folded and placed upon the back element 2, and upper and lower end flaps 5 and 6 are folded thereover, and finally the side flaps 3 and 4 are laid over the folded canopy 10 and the end flaps 5 and 6, the snap-fastener elements 11 and 12 snap together. The juvenile wearer then places his arms through the loop provided by the shoulder straps 27, and the girth strap or belt 21 is snapped together at his front. The structure then appears as shown in Fig. 2.

It will be noted that the rip cord 19 is adapted to extend over the shoulder of the wearer, where it dangles on his chest, and may be provided with a ring, not shown, if desired. When the rip cord 19 is pulled, the snap fasteners 11 and 12 separate, and the side flap 3 is pulled laterally away from frictional engagement with the underlying side flap 4. Thereafter, the short end flap 6 is freed from frictional engagement with the side flap 4 and drops vertically downwardly to the position of Fig. 1. The upper end flap 5, because of its extreme lack of height, also exerts a minimum of frictional engagement upon the folded canopy 10 and the shroud lines 7, whereupon these elements are permitted to drop downwardly, almost immediately, to the position of Fig. 1. Because of the ease of packing and of releasing the chute 10 and shroud lines 7 from the back element 2, these steps may be repeated as frequently as desired by the juvenile wearer.

My invention has been thoroughly tested and found to be completely satisfactory in the accomplishment of the above objects, and while I have shown a preferred embodiment thereof, it should be obvious that same is capable of modification without departure from the scope of the appended claim.

What I claim is:

A toy parachute and pack therefor including, a generally rectangular back forming element formed from flexible sheet material, side and upper and lower end flaps on said back element, shroud lines connected to the intermediate portion of said back element, a toy canopy on the free ends of said shroud lines, a girth strap rigidly connected to the lower end portion of said back element, a pair of shoulder straps connected in spaced relation at their forward ends to the front portions of said girth strap and at rear end portions to said back element and said girth strap, means on the front end of said girth strap intermediate said shoulder straps for detachably securing the opposite ends of said girth strap together, cooperating snap-fastener means adjacent the free edge portion of one of said side flaps and adjacent the inner edge portion of the other of said side flaps, and a rip cord having one end secured to the outermost of said side flaps closely adjacent the snap-fastener element thereon, the free end of said rip cord adapted to extend over the shoulder and onto the chest portion of the wearer, said side flaps being substantially the same shape and area as the back element, said upper and lower end flaps being substantially the same width as the back element but less than one-half the height thereof.
